JOHN K. GUTHRIE, OF PERTH ROAD, ONTARIO, CANADA, ASSIGNEE OF ONE-HALF TO
JOHN B. HENNIGER, OF SMITHS FALLS, ONTARIO, CANADA.

TELEPHONE-CALL RECORDER.

1,123,734.

Specification of Letters Patent. Patented Jan. 5, 1915.

Application filed May 11, 1914. Serial No. 337,817.

To all whom it may concern:

Be it known that I, JOHN K. GUTHRIE, a subject of the King of Great Britain, residing at Perth Road, in the Province of Ontario, Dominion of Canada, have invented certain new and useful Improvements in Telephone-Call Recorders; and I do hereby declare the following to be a full, clear, and exact description of the invention, such as will enable others skilled in the art to which it appertains to make and use the same.

This invention relates to recording devices and has special reference to a device adapted to be used in conjunction with telephones of either the wall or stand type, for recording the number of calls used.

It is well known among the subscribers of telephone companies that when one has a limited phone service it is extremely desirable to be able to keep account of the number of calls used in order that the prescribed number may not be carelessly exceeded and in order to check up the report of the telephone company. Devices for this purpose have been designed and have so many disadvantages that they have not come into popular use. The disadvantage of many of these devices is that every time the receiver hook is moved a call is registered which should not be the case as a subscriber has frequently to move the receiver hook repeatedly to attract the attention of the central operator. To overcome these disadvantages this invention has been designed and so constructed that the recording device may or may not be operated by the movement of the receiver hook at the will of the operator.

An important object is to provide a device of this character which may be quickly, readily, and adjustably connected with any style of telephone.

Other objects and advantages, such as simplicity, cheapness, efficiency in operation, durability in service, and the general improvement of the art will be carefully brought out in the following description and illustrated in the accompanying drawings, in which,

Figure 1 is a front elevation of a telephone with my device applied thereto, Fig. 2 is a side elevation thereof, Fig. 3 is a horizontal section below the transmitter, and, Fig. 4 is a detail perspective view of the clips and supporting bracket.

Referring more particularly to the drawings, the numeral 5 designates any well known or preferred type of telephone comprising the usual base 6, standard 7 carrying the transmitter 8 and having the laterally extending receiver hook 9 adapted to support the receiver 10. All these parts are old and well known and consequently no further description of them will be made.

My novel recording device comprises two members, one attached to the receiver 10 and the other attached to the standard 7, each of these members being adapted to coöperate. The member disposed upon the standard 7 comprises a pair of circular clips 11 provided with ears 12, the clips 11 being spaced apart upon the standard 7 and connected by a bar 13 having a longitudinal slot 14 formed therein for the reception of the stem 15 secured to the casing 16 of a recorder 17. By this means it will be seen that the recorder may be moved vertically upon the bar 13 and be clamped in any desired position thereon by means of a thumb or wing nut 18 engaging the screw-threaded end of the stem 15.

The recorder 17 is operated by means of a laterally extending arm 19 which extends into the casing of the recorder and actuates the step-by-step ratchet movement for moving the hands 20 upon the graduated dial 21 of the recorder. The dial 21 is divided preferably into a hundred graduations, over which the larger of the hands 20 travels, moving one graduation every time the arm 19 is moved downwardly. In order to record a very large number of calls the dial 21 may be provided with another set of graduations traveled over by the smaller of the hands 20, one complete revolution of the larger hand moving the smaller hand one graduation. When the recorder 17 is mounted upon the bar 13 and properly adjusted thereon, the arm 19 will extend in an upwardly and inclined direction substantially parallel with the receiver hook 9.

In order that the arm 19 may be actuated for operating the recorder, I provide a member 22 upon the receiver 10. The member 22 comprises a ring 23 having its ends separated and provided with lugs 24 between which is disposed a block 25 conforming in contour to the lugs 24, the lugs 24 and block 25 being secured together by a screw 26 passing through them and clamp- 110

ing the member securely adjacent the smaller end of the receiver 10. The lugs 24 and block 25 are adapted to be disposed above the arm 19 of the recorder 17 and engage the arm 19 when the receiver hook 9 is depressed.

The operation of the device is as follows: Assuming that the parts are arranged in the position shown in the drawings, the receiver hook 9 is in its lowest position, the arm 19 is in its lowest position, and the phone is in readiness to be used. When the phone call is made and the receiver 10 removed from the hook 9 the arm 19 of the recorder will move upwardly by virtue of a spring contained within the recorder. When it is desired to ring off or sever connection with the telephone line, the receiver 10 is placed upon the hook 9 in the usual manner, with the lugs 24 facing toward the user of the phone, whereupon the weight of the receiver will depress the hook 9, as is well known, and the lugs 24, by virtue of their engagement with the arm 19, will move the arm 19 downwardly, causing the recorder 17 to operate and moving the larger hand one graduation. If it is not desired to record the call, as for instance, when a wrong number is given by the central operator or in any other instance in which the call would not be charged for, the receiver would be placed upon the hook with the lugs 24 facing in the opposite direction so that they would not engage the arm 9, whereupon, of course, the recorder would not be operated. If it is found necessary to move the hook 9 up and down repeatedly to attract the attention of the central operator, the arm 19 would not be moved and therefore no recording would be done.

By providing the clips 11 clamped upon the standard 7, the recorder and its associated parts may be readily adjusted vertically upon the standard and, furthermore,

the provision of the slot 14 in the bar 13 enables the recorder to be adjusted independently upon the bar 13 so that the arm 19 will extend in the proper direction and at the correct height to be actuated when engaged by the lugs on the receiver.

From the foregoing, it will be apparent that thus I have provided a novel, simple, and efficient means for recording the number of calls over a telephone and at the same time allow the receiver hook to be moved absolutely independently of any recording action.

It will be readily understood that I may make various changes in the form, construction, and arrangement of parts without departing from the spirit of the invention or limiting the scope of the subjoined claim, as for instance I may omit the clips and provide lugs upon the ends of the bar 13 whereby the bracket may be attached to a wall phone instead of a phone having a tubular standard.

Having thus described my invention, what I claim is:—

An attachment for "desk" telephones, comprising a longitudinally slotted plate having terminal clamps for engagement with the standard of the telephone, and a recording device having at one side a stem slidably disposed in the slot of the plate and means for holding the stem at any point of its sliding movement, said recording device including an actuating lever of a length to be positioned in the path of movement of a lateral extension of a receiver, as the receiver is moved into engagement with the hook that projects from the standard.

In testimony whereof, I affix my signature, in the presence of two witnesses.

JOHN K. GUTHRIE.
